UNITED STATES PATENT OFFICE.

GEORGE J. LOWRES, OF NEWARK, NEW JERSEY, ASSIGNOR TO LOWRES OPTICAL COMPANY, A CORPORATION OF NEW JERSEY.

EYEGLASS-MOUNTING.

965,917.

Specification of Letters Patent. Patented Aug. 2, 1910.

Application filed March 26, 1910. Serial No. 551,776.

To all whom it may concern:

Be it known that I, GEORGE J. LOWRES, a citizen of the United States, residing at Newark, in the county of Essex and State 5 of New Jersey, have invented certain new and useful Improvements in Eyeglass-Mountings; and I do hereby declare the following to be a full, clear, and exact description of the invention, such as will enable 10 others skilled in the art to which it appertains to make and use the same, reference being had to the accompanying drawings, and to characters of reference marked thereon, which form a part of this specification. 15 The present invention relates, generally, to an improvement in eye-glasses; and, the present invention has reference, more particularly, to improvements in finger-piece mountings for eye-glasses.

20 The present invention has for its principal object to provide an improved finger-piece mounting for eye-glasses having nose-grips that may be conveniently operated by the wearer's fingers in applying and removing 25 the eye-glasses, the construction of the mounting being simple, easy of manipulation, and of a compact and slight appearance.

A further object of the present invention 30 is to provide a simple and easily applied spring-means for actuating the nose-grips of the mounting and cause the same to effectively grip the nose of the wearer to retain the eye-glasses in place. This said 35 spring-means being so constructed that it may be applied to a great variety of styles and designs of nose-grips and finger-pieces with great ease; and, furthermore, the construction of said spring-means being such, 40 that the danger of the accidental breaking of the spring, or the displacing or disarranging of the same, when wiping or cleaning the eye-glasses is greatly minimized, if not entirely obviated. Furthermore, the 45 spring-means is so constructed that the mechanical processes of applying the same to a mounting, or replacing the same upon 50 mountings, is greatly simplified and reduced. This spring-means is also of such simple construction that it may be put on an eye-glass mounting of any make or manufacture without the aid of a skilled mechanic.

Other objects of the present invention not

at this time more particularly enumerated 55 will be clearly understood from the following detailed description of my present invention.

With the various objects of the present invention in view, the said invention consists, primarily, in the novel construction 60 of eye-glass mountings, and particularly the actuating spring-means therefor, herein-after set forth; and, furthermore, this invention consists in the several novel arrangements and combination of the various 65 devices and parts, as well as in the details of the construction thereof, all of which will be more fully described in the following specification, and then finally embodied in 70 the clauses of the claims which are appended to and which form an essential part of this specification.

The invention is clearly illustrated in the 75 accompanying drawings, in which:—

Figure 1 is a large plan view of a mounting for eye-glasses provided with the novel actuating spring-means embodying the principles of my present invention; and Fig. 2 is a similar detail view, illustrating the operation of the nose-grip and fingerpiece in connection with the novel actuating spring-means, when spreading or opening the nose-grips to apply the eyeglasses to the nose of the wearer. Fig. 3 is a longitudinal cross- 85 section, said section being taken on line 3—3 in said Fig. 1, looking in the direction of the arrow x; and Fig. 4 is a detail cross-section, taken on line 4—4 in said Fig. 1, looking in the direction of the arrow y. Fig. 5 is a 90 perspective view of a blank from which the novel actuating spring-means is formed; Fig. 6 is another perspective view, illustrating the first step in the formation of said actuating spring-means from the blank 95 shown in said Fig. 5; and Fig. 7 is a large perspective view of the completed actuating spring-means embodying the principles of the present invention, when it is finished and ready to be applied to an eye-glass mounting. 100

Similar characters of reference are employed in all of the said herein-above described views, to indicate corresponding parts.

Referring now to the several figures of the drawings, the reference-character 1 indicates an eye-glass mounting comprising the lenses

2 connected by a bridge 3, the latter being provided with the usual forked ends 4 which serve to hold or retain the said lenses 2. The said bridge is also provided at the rear of 5 said forked ends 4 with oppositely extending retaining lugs 5 which are adapted to form the seats for said lenses 2. The said bridge is further provided at a point adjacent to its forked ends 4 with base or seat- 10 portions 6 upon which may be mounted nose-grips and their finger-pieces, as will be herein-after more fully described. Pivotaly mounted on said base or seat-portions 6 of the said bridge 3 are finger-pieces 7, which 15 may be of any desirable construction.

The herein illustrated finger-piece is provided with forwardly extending arms 8 forming the manipulating portions thereof, and which are adapted to be engaged by 20 the fingers of the wearer to operate the same; and, are further provided with rearwardly extending portions 9, each portion terminating in an upwardly extending arm 10. Pivotaly connected with the upwardly 25 extending arms 10 of said finger pieces 7 are nose-grips 11, of any desirable construction and design. Of course it will be clearly understood that, if it is so desired, the said finger-pieces and nose-grips may be combined to form one integral part.

The novel actuating spring-means comprises, substantially, a blank, such as is shown in Fig. 5, the same comprising a washer-like member or element 12 provided 35 with a perforation 13, said washer-like member having an elongated portion or tongue 14. Integrally connected with said washer-like member 12 is an outwardly extending portion 15 which is provided with a right-angled extension 16 having a hook-shaped end 17. The said blank thus formed is bent at the point where said outwardly extending portion 15 joins said washer-like member 12, so as to bring the extension 16 at right angles thereto, as clearly shown in Fig. 6. The 40 said extension 16 is then coiled to form a helical coil or spring 18, the plane of its cross-section being at right angles to said washer-like member 12, and its coils or 45 helices being arranged so as to be presented above said washer-like members 12, to register the inner coil of said spring thus formed above the perforation 13 of said washer-like member 12, as will be clearly 50 evident from an inspection of the drawings. The said hook-shaped end 17 of the spring, thus formed, extends outwardly, all in a manner shown more particularly in Fig. 7 of said drawings. The said actuating spring- 55 means constructed as above described is now assembled in its operative connection with the eyeglass mounting. The said washer-like member 12 is placed above the finger-piece 7, a retaining screw 19 being inserted 60 through the perforation 13 of said washer-

like member 12, the same passing through a perforation 20 in said finger-piece 7, so as to form the fulcrum for said finger-piece, and then being screwed into said base or seat-portion 6 of the said bridge 3. The end 21 70 of said retaining screw 19 may be crushed or riveted over, if desired, to prevent any accidental displacement of the same. The elongated portion or tongue 14 of said washer-like member 12 bears against one of 75 the retaining lugs 5, so as to serve as a stop for retaining said coil or helical spring 18 in its operative relation with said finger-piece when the hooked end 17 of said coil or helical spring 18 is hooked over the rearwardly extending portion 9 of said finger-piece 7, the tension of said coil or helical spring 18, when thus arranged, tending to press or force the nose-grip 11 connected 80 with said finger-piece toward the nose of 85 the wearer to retain the eye-glasses in place. In applying the eye-glasses to the nose of the wearer, the said manipulating portions of said fingerpieces 7 are engaged by the fingers and pressed toward each other, this operation tending to turn the finger-pieces 7 on their fulcrums and thus spread apart the nose-grips 11, carried upon the opposite ends 90 of said finger-pieces. This movement of the said finger-pieces is transmitted through 95 the hook-shaped ends 17 of said coiled or helical springs 18, serving to tighten the coils of said springs and thereby increases the tension upon the said finger-pieces 7, so that when the mounting is brought in proper 100 position with relation to the nose of the wearer, and the pressure of the finger is released from the manipulating portions of said finger-pieces, these coiled springs tend to unwind, and thus pull back the finger-pieces to their initial normal positions, so that the said nose-grips 11 are pressed 105 against the nose of the wearer, all of which operations will be clearly understood from an inspection of Figs. 1 and 2 of the accompanying drawings.

It will thus be seen, that a very simple and effectively operating actuating spring for each finger-piece and the nose-guards of an eye-glass mounting is provided; and the 110 same is of such a construction, that it can easily be applied and used with almost any styles of fingerpieces and nose-guards. It will also be seen that the said actuating spring-means is of a very durable and strong 115 construction, rendering it less likely to be broken or accidentally displaced from its operative connection with the eye-glass mounting.

I am aware that some changes may be 120 made in the various arrangements and combinations of the several parts, as well as in the detailed construction of the several parts of my present invention without departing 125 from the scope thereof, as described in the 130

foregoing specification and as defined in the appended claims. Hence, I do not limit my invention to the exact arrangement and combinations of the various parts as set forth in the foregoing specification, nor do I confine myself to the details of the construction of the said parts, as illustrated in the accompanying drawings.

I claim:

- 10 1. In eye-glasses, the combination with the bridge, of pivotally mounted nose-grips, helical springs mounted in connection with said bridge and nose-grips, said helical springs having washer-like members integrally formed therewith forming the anchor-joints of said helical springs, and a hook-shaped end connected with each helical spring adapted to engage said pivotally mounted nose-grips.
- 20 2. In an eye-glass mounting, the combination with a support carrying a pivotally mounted nose-grip, a helical-spring, a washer-like member integrally formed with said helical spring, an elongated portion or tongue connected with said washer-like member adapted to engage a portion of said support so as to anchor said helical spring, and a hook-shaped portion upon the free or movable end of said helical spring adapted 30 to engage said nose-grip to turn the same on its pivot.
3. In an eye-glass mounting, the combination with a bridge, of forked ends for supporting lenses in connection therewith, a base or seat inwardly from said forked ends, a finger-piece carrying a nose-grip pivotally mounted on said base or seat, a helical-spring arranged in a horizontal plane above said finger-piece, said helical spring having 40 a perforated washer-like member integrally formed therewith and bent beneath the coils of said helical spring, a retaining screw for connecting said helical spring upon the mounting, said retaining screw passing through the perforation of said washer-like member so as to screw into said base or seat and also form the pivot for said finger-piece, an elongated portion or tongue connected with said washer-like member adapted to 50 engage a portion of the forked end of said bridge to retain said washer-like member and the end of said helical spring connected therewith from movement, and a hook-shaped end connected with said helical spring adapted to hook over said finger-piece, so that the tension of said helical spring may be exerted upon said finger-piece to turn the same and the nose grip carried thereby on its pivot.
- 60 4. An actuating spring for eye-glass mountings provided with pivotally connected nose-grip devices, comprising a helically coiled spring-body, a washer-like member integrally formed with the inner end of said 65 coiled spring-body and extending in a hori-

zontal plane beneath the coils of said spring-body, and a hook-portion connected with the opposite or outer end of said helically coiled spring-body.

5. An actuating spring for operating the pivotally connected nose-grip devices of an eye-glass mounting, comprising a helically coiled spring-body, an integrally formed perforated washer-like member connected with the inner end of said helically coiled spring-body, said washer-like member being bent with relation to the helically coiled spring-body, so as to present its perforation in registration with the center of said helical coils of said spring-body.

6. An actuating spring for operating the pivotally connected nose-grip devices of an eye-glass mounting, comprising a helically coiled spring-body, an integrally formed perforated washer-like member connected with the inner end of said helically coiled spring-body, said washer-like member being bent with relation to the helically coiled spring-body, so as to present its perforation in registration with the center of said helical coils of said spring-body, and a hook-member formed upon the outer or free end of said helically coiled spring-body adapted to engage a portion of said pivotally connected nose-grip devices.

7. An actuating spring for operating the pivotally connected nose-grip devices of an eye-glass mounting, comprising a helically coiled spring-body, an integrally formed perforated washer-like member connected with the inner end of said helically coiled spring-body, said washer-like member being bent with relation to the helically coiled spring-body, so as to present its perforation in registration with the center of said helical coils of said spring-body, said washer-like member being further provided with an elongated portion or tongue adapted to serve as a stop to engage a portion of said eye-glass mounting, when said actuating spring is assembled therewith to retain the same in its fixed relation thereto.

8. An actuating spring for operating the pivotally connected nose-grip devices of an eye-glass mounting, comprising a helically coiled spring-body, an integrally formed perforated washer-like member connected with the inner end of said helically coiled spring-body, said washer-like member being bent with relation to the helically coiled spring-body, so as to present its perforation in registration with the center of said helical coils of said spring-body, said washer-like member being further provided with an elongated portion or tongue adapted to serve as a stop to engage a portion of said eye-glass mounting, when said actuating spring is assembled therewith to retain the same in its fixed relation thereto, and a hook-member formed upon the outer or free end of

said helically coiled spring-body adapted to engage a portion of said pivotally connected nose-grip devices.

9. An actuating spring for operating the pivotally mounted nose-grip devices of an eye-glass mounting, comprising a helical spring, the inner end of the coil of said helical spring having an enlarged perforated portion bent at right angles to the cross-section of the coils of said helical spring and extending beneath said coils, so as to present its perforation beneath the center of said coils.

10. An actuating spring for operating the pivotally mounted nose-grip devices of an eye-glass mounting, comprising a helical spring, the inner end of the coils of said helical spring having an enlarged perforated portion bent at right angles to the cross-section of the coils of said helical spring, and extending beneath said coils, so as to present its perforation beneath the center of said coils, and the outer end of said helical spring having a downwardly extending hook-shaped portion.

11. An actuating spring for operating the pivotally mounted nose-grip devices of an eye-glass mounting, comprising a helical spring, the inner end of the coil of said helical spring having an enlarged perforated portion bent at right angles to the cross-section of the coils of said helical spring, and extending beneath said coils, so as to present its perforation beneath the center of said coils, said enlarged portion having an outwardly extending lug forming a stop-member.

12. An actuating spring for operating the pivotally mounted nose-grip devices of an eye-glass mounting, comprising a helical spring, the inner end of the coil of said helical spring having an enlarged perforated portion bent at right angles to the cross-section of the coils of said helical spring, and extending beneath said coils, so as to present its perforation beneath the center of said coils, said enlarged portion having an outwardly extending lug forming a stop-member, and the outer end of said helical spring having a downwardly extending hook-shaped portion.

13. In an eye-glass mounting, a bridge, forked ends connected therewith, adapted to receive lenses, a base or seat-portion inwardly from each forked end, a pivot-member connected with each base or seat-portion, a finger-piece movably mounted upon each pivot-member, each finger-piece consisting of a rearwardly extending end of said finger-piece, forwardly extending arm, a nose-grip connected with each rearwardly extending end, and said forwardly extending arms forming manipulating portions for turning said finger-pieces and the nose-grips connected therewith on said pivot-

members, an actuating spring adapted to engage each finger-piece, comprising a helical spring, the inner end of the coil of said helical spring having an enlarged perforated portion bent at right angles to the cross-section of the coil of said helical spring and extending beneath said coil, so as to present its perforation beneath the center of said coil, the said perforation of said enlarged portion being adapted to receive the end of said pivot-member to connect said actuating spring operatively with said mounting.

14. In an eye-glass mounting, a bridge, forked ends connected therewith, adapted to receive lenses, a base or seat-portion inwardly from each forked end, a pivot-member connected with each base or seat-portion, a finger-piece movably mounted upon each pivot-member, each finger-piece consisting of a rearwardly extending end and a forwardly extending arm, a nose-grip connected with each rearwardly extending end, and said forwardly extending arms forming manipulating portions for turning said finger-pieces and the nose-grips connected therewith on said pivot-members, an actuating spring adapted to engage each finger-piece, comprising a helical spring, the inner end of the coil of said helical spring having an enlarged perforated portion bent at right angles to the cross-section of the coil of said helical spring and extending beneath said coil, so as to present its perforation beneath the center of said coil, the said perforation of said enlarged portion being adapted to receive the end of said pivot-member to connect said actuating spring operatively with said mounting.

15. In an eye-glass mounting, a bridge, forked ends connected therewith, adapted to receive lenses, a base or seat-portion inwardly from each forked end, a pivot-member connected with each base or seat-portion, a finger-piece movably mounted upon each pivot-member, each finger piece consisting of a rearwardly extending end and a forwardly extending arm, a nose-grip connected with each rearwardly extending end, and said forwardly extending arms forming manipulating portions for turning said finger-pieces and the nose-grips connected therewith on said pivot-members, an actuating spring, adapted to engage each finger piece, comprising a helical spring lying in a horizontal plane with relation to said fingerpiece, the inner end of the coil of said helical spring having an enlarged perforated portion bent at right angles to the cross-section of the coil of said helical spring and extend-

ing beneath said coil, so as to present its perforation beneath the center of said coil, the said perforation of said enlarged portion being adapted to receive the end of said 5 pivot-member to connect said actuating spring operatively with said mounting, and a hook-shaped member connected with the outer end of the coil of said actuating spring adapted to engage the rearwardly extending portion of said fingerpiece to turn the same and its nose-grip toward the nose of the wearer.

16. In an eye-glass mounting, a bridge, forked ends connected therewith adapted to receive lenses, a base or seat-portion inwardly from each forked end, a pivot-member connected with each base or seat-portion, a finger-piece movably mounted upon each pivot-member, each finger-piece consisting 20 of a rearwardly extending end and a forwardly extending arm, a nose-grip connected with each rearwardly extending end, and said forwardly extending arms forming manipulating portions for turning said fingerpieces 25 and the nose-grips connected therewith on said pivot-members, an actuating spring, adapted to engage each finger-piece, comprising a helical spring lying in a horizon-

tal plane with relation to said fingerpiece, the inner end of the coil of said helical spring having an enlarged perforated portion bent at right angles to the cross-section of the coil of said helical spring and extending beneath said coil, so as to present its perforation beneath the center of said coil, 30 the said perforation of said enlarged portion being adapted to receive the end of said pivot-member to connect said actuating spring operatively with said mounting, said enlarged portion having an outwardly extending lug forming a stop-member adapted to engage the forked ends of said bridge to prevent said actuating spring from turning upon said pivot, and a hook-shaped member 35 connected with the outer end of the coils of said actuating spring adapted to engage the rearwardly extending portions of the fingerpiece to turn the same and its nose-grip toward the nose of the wearer.

In testimony, that I claim the invention 50 set forth above I have hereunto set my hand this 23rd day of March, 1910.

GEORGE J. LOWRES.
